UNITED STATES PATENT OFFICE.

CHARLES T. LAMBIN, OF MONTREAL, QUEBEC, CANADA, ASSIGNOR OF ONE-HALF TO
SAMUEL VENIS, OF MONTREAL, CANADA.

REFRIGERATING APPARATUS.

Application filed February 25, 1924, Serial No. 694,956. Renewed August 19, 1926.

The present invention pertains to a novel refrigerating apparatus and resides primarily in a refrigerating apparatus in which the pump for compressing the ammonia into the reservoir and drawing it from the evaporation coils is double acting. The pump has a single inlet connected to the evaporation coils and a single outlet connected to the reservoir.

10 The principal advantage of this improvement is a significant increase in efficiency over other refrigerating apparatus of the same capacity. The fact that the pump piston performs work on both strokes decreases the percentage of energy lost due to friction. Consequently there is less heat developed than in apparatus having a single acting pump. It is particularly desirable in an ammonia compressor to hold the amount 20 of frictional heat as low as possible, since this heat causes an expansion of gas which is contrary to the function of the system. A double acting pump capable of performing a given amount of work produces half as 25 much friction as a single acting pump performing the same amount of work. Consequently, the heat of friction is reduced by one half in an apparatus of a given capacity by the provision of a double acting pump, 30 from which it follows that the amount of work required to overcome the expansion resulting from the heat of friction is also reduced by one half.

35 A further advantage of applying a double acting pump in a refrigerating apparatus is that the back pressure from the reservoir aids the movement of the piston in either direction. The back pressure, acting against both faces of the piston at all times, 40 is neutralized, whereas in a single acting pump an extra amount of work is required to overcome the back pressure against the forward face of the piston during the compression stroke.

45 Still another advantage of the invention is that the operation is continuous. In other words, the pump has but a single inlet connected to the evaporation coils and a single outlet connected to the reservoir, as a consequence of which the pump draws and discharges in a continuous manner as distinguished from the intermittent operation characteristic of a single acting pump.

50 The invention provides further for a compact refrigerating plant consisting substan-

tially of a unitary mass, whereby it can be transported from place to place without requiring dismantling. To this end, the base of the machine is in the nature of a receptacle in which are contained the refrigerant 60 tank and the condensing coil. Upon the receptacle are mounted the pump and a motor for driving the same. The outlet end of the pump is connected to the condensing coil, while the inlet end is connected to the evaporation coil. The pump is surrounded by a water jacket in fluid communication with the interior of the receptacle, and suitable means are provided for the circulation of water through the packet and receptacle. 70 As a result of this construction, the parts that require cooling are cooled in a single stream, and the volume of water per unit of surface to be cooled is large in comparison with the systems hitherto in use. 75

The invention is fully disclosed in the following description and in the accompanying drawings in which:

Figure 1 is a side elevation of the apparatus;

Figure 2 is a section on the line 2—2 of Figure 1;

Figure 3 is a diagrammatic horizontal section of the pump;

Figure 4 is a vertical section of the apparatus;

Figure 5 is a plan view thereof with the cover removed;

Figure 6 is a longitudinal vertical section of the pump;

Figure 7 is a longitudinal horizontal section of the pump;

Figures 8, 9 and 10 are sections on the lines 8—8, 9—9 and 10—10 respectively of Figures 6 and 7; and,

Figure 11 is an enlarged detail of Figure 9.

Reference will now be had to these views by means of like characters which are employed to designate corresponding parts throughout.

The device comprises a base constituting a cooling receptacle 1 in the bottom of which is contained an ammonia tank 2 having an annular chamber, as illustrated in Figure 4, 105 as a consequence of which there exists a longitudinal bore 3 therethrough. Above the tank is provided a sinuous pipe 4 for communicating with the tank, a valve 5 being interposed. An outlet pipe 6 is also con-

80

105

110

nected to the tank and is provided with a valve 7. The valves 5 and 7 have handles 5' and 7' respectively passing through the adjacent wall of the receptacle, whereby the 5 inlet or outlet of the tank 2 may be cut off from an exterior point in case of defective circulation or for other reasons.

At the top of the member 1 is formed the lower half 8 of a crank case for the pump 10 mechanism subsequently to be described. In the walls of the section 8 is journaled a shaft 9 formed with a crank 10 intermediate its ends. A cover 11 is adapted to fit upon the portion 8 to form a closed housing.

15 The shaft 9 carries at one end a worm wheel 12 meshing with a worm 13. Upon the member 1 is also mounted a motor 14, the shaft 15 of which carries a sprocket wheel 16. A similar wheel 17 is mounted on the 20 shaft of the worm 13, and the two wheels are joined by a sprocket chain 18.

Adjacent one end of the housing 8-11, the member 1 supports a cylinder 19. The 25 ends of this member are closed by blocks or heads 20 and 21 at the forward and rear ends respectively. Within the cylinder is provided a piston 22 having a rod 23 passing through the rear head 21. A pair of 30 guides 24 are formed at the side walls of the housing 8-11, and the piston rod carries a crosshead 25 slideable on the guides. The free end of the rod is connected to the crank 10 by means of a connecting arm 26.

Within the head 21 is formed a gland 35 comprising a pair of spaced washers 27, the outer one being held in place by a nut 28. The space between the washers is filled with a quantity of mercury designated by the numeral 29 which extends upwardly into a bore 30 drilled in the upper part of the head. The upper end of the bore is closed by a plate 31, there being a washer 32 interposed. In the event that the gas compressed behind the piston leaps into the 45 packing, it will flow through the mercury and collect at the surface thereof, there establishing a downward pressure of the mercury against the washers to tighten the latter around the piston rod.

50 The cylinder is surrounded by a water jacket 33, and the top of the receptacle 1 has a slot 34 which places the water jacket in communication with the interior of the reservoir 1. Water is admitted to the reservoir through a pipe 35, and is permitted to flow out of the jacket through a pipe 36 at the top thereof (Figure 1).

Each head is formed with a pair of valve chambers designated by the numerals 37 55 and 38 in the forward head and by the numerals 39 and 40 in the rear head. Since these chambers are formed by drilling through the tops of the heads, the upper ends thereof are closed by means of plates 31 and 41. The chambers are formed with

valve seats 37', 38', 39' and 40' respectively adapted to be closed by the ball valves 37'', 38'', 39'' and 40'' respectively. In the wall of the cylinder are cut a pair of longitudinal channels 43 and 44 disposed diametrically opposite each other with reference to the chamber 45 of the cylinder and in horizontal alinement, as indicated in Figures 3 and 7. In the heads are cut ducts 46, 47, 48 and 49 in alinement with the channels and consequently outside the periphery of the chamber 45, as is evident from Figures 3, 8 and 9. The ducts 46 and 48 are disposed beneath the level of the valves 37'' and 39'', while the ducts 47 and 49 are arranged above the level of the valves 38'' and 40''. The ducts are placed in communication with the valve chambers by means of passages 50, 51, 52 and 53 cut from the sides of the heads. One of these passages 50 receives the gas inlet pipe 54, while the remaining ones are plugged as at 54'.

The chamber 45 communicates with the valve chambers through ports 55 and 56 in the forward head and similar ports 57 and 58 in the rear head. The ports 55 and 57 are disposed above the level of the valves 37'' and 39'' respectively, while the remaining ports 56 and 58 lie beneath the level of the ports 38'' and 40'' respectively. In the forward head is cut a vertical passage 59 communicating at its upper end with the valve chamber 38 and receiving at its lower end the inlet end of the condensing coil 4.

A set of evaporation coils 60 has its upper and lower ends communicating with the gas inlet and outlet pipes 54 and 6 respectively. These coils may be located at any desired place and may be of any desired shape or size, as is well known in the art. The branch 60' which extends to the outlet pipe 6 of the reservoir 2 is provided with gages 61 for an obvious purpose.

The operation of the pump will be best understood by reference to Figure 3 which 110 diametrically shows the channels, ports and ducts in the same horizontal plane. On the rearward stroke of the piston the suction takes place through the port 55, raising the valve 37'' and drawing gas from the coils 60, through the pipe 54, duct 55 and into the chamber 45. The same stroke also produces suction through the port 56, drawing the valve 38'' upon its seat and obstructing the communication between the channel 43 and the valve chamber 38. The pressure increasing at the rear of the piston is exerted through the ports 57 and 58 in the rear head, closing the valve 39'' to the channel 44 and forcing the valve 40'' off its seat, thus bringing the channel 43 into communication with the cylinder chamber 45 through duct 49, valve chamber 40 and port 59. The gas which is thus compressed at the rear of the piston travels through the channel 43

to the forward head, where it flows through the duct 47 and around the closed valve 38" into the passage 51 and thence to the condensing coils 4 and reservoir 2.

5 On the forward stroke of the piston the valves 37" and 40" are closed while the valves 38" and 39" are raised from their seats by the pressure and suction acting through the various ports in a manner similar to that already described. The suction through the open valve 39" acts through port 57 and duct 48 in the rear head, causing a rearward draft through the channel 44 which is now closed to the valve chamber 37. Consequently, the reduced pressure within the channel 44 serves to draw vapor from the coils 60 through the inlet pipe 46, which finds its way to the rear of the piston. A portion of the gas compressed in advance of the piston passes through the open valve 38", through the duct 47 and rearwardly through the channel 43, but is here obstructed by the closed valve 40". The remainder of the gas passes around the valve 38" and through the passage 59 to the condensing coils 4. It will thus be apparent that on either stroke of the pump gas is continuously drawn into the pump chamber through the inlet pipe 54 and is expelled under pressure through the passage 59 into the condensing coils 4.

Due to this continuous operation the ratio between the loss in friction and the power of the pump is considerably decreased as already pointed out. A machine of usual construction having the single acting pump, driven at 250 revolutions per minute and requiring a cylinder not greater than 4 inches long can be replaced by a machine having a double acting pump and driven at 60 revolutions per minute. This machine can carry a 9 inch cylinder and produce the same quantity of refrigeration as the machine of greater speed. The decrease in speed results in a further reduction of friction although consideration is taken of the fact that a longer cylinder is provided. Since the heat developed by friction, whatever be the quantity, counteracts the function of the pump, it will be apparent that a decrease in the heat of friction is a significant consideration in an ammonia apparatus.

It will also be observed that the back pressure against the piston during either stroke will aid the stroke by balancing the pressure at the advancing side.

While a specific embodiment of the invention has been illustrated and described, it is to be understood that various alterations in the details of construction may be made without departing from the spirit of the invention as indicated by the appended claims.

Having thus fully described the invention, what I claim as new and desire to protect by Letters Patent is:—

1. A refrigerating system comprising a receptacle having an integral crank case housing formed at the top thereof and a slot in said top adjacent said housing, a refrigerant tank disposed in said receptacle, a pump cylinder resting on the top of the receptacle, a water jacket surrounding the cylinder and disposed over said slot to communicate therewith, a piston in the cylinder, means within the housing for actuating said piston, a coil disposed within the receptacle and extending from the pump cylinder to the refrigerant tank, and means for permitting a flow of water through said water jacket and receptacle.

2. A refrigerating system comprising a receptacle having an integral crank case housing formed at the top thereof and a slot in said top adjacent said housing, a refrigerant tank with an annular chamber disposed in said receptacle, a pump cylinder mounted on the top of the receptacle, a water jacket surrounding the cylinder and disposed over said slot to communicate therewith, a piston in the cylinder, means within the housing for actuating said piston, a coil disposed within the receptacle and extending from the pump cylinder to the refrigerant tank, and means for permitting a flow of water through said water jacket and receptacle.

3. A refrigerating system comprising a base having the form of a receptacle, a refrigerant tank mounted in said receptacle, means for permitting a flow of water through said receptacle, a pump mounted on said receptacle, a condensing coil having one end connected to the pump, the remaining end of the coil being connected to the refrigerant tank, an outlet pipe extending from said tank, valves in said coil and outlet pipe in close proximity to said tank, said valves having handles projecting through a wall of the receptacle.

4. A refrigerating system comprising a base having the form of a receptacle, a refrigerant tank mounted in said receptacle, means for permitting a flow of water through said receptacle, a crank case section formed at the top of the receptacle and integral therewith, a cylinder mounted adjacent said section, a cover for completing said section, pump mechanism in said cylinder and crank case, a condensing coil having one end connected to the outlet of said cylinder, the remaining end of the coil being connected to the refrigerant tank.

In witness whereof I have hereunto set my hand.

CHARLES T. LAMBIN.
